UNITED STATES PATENT OFFICE.

GEORGE DEBELACK AND ALEXANDER DEBELACK, OF SHEBOYGAN, WISCONSIN.

GAME ATTACHMENT FOR POCKET-BILLIARD TABLES.

1,409,527.

Specification of Letters Patent. Patented Mar. 14, 1922.

Application filed September 29, 1919. Serial No. 327,203.

To all whom it may concern:

Be it known that we, GEORGE DEBELACK and ALEXANDER DEBELACK, citizens of the United States, residing at Sheboygan, in the county 5 of Sheboygan and State of Wisconsin, have invented certain new and useful Improvements in Game Attachments for Pocket-Billiard Tables; and we do declare the following to be a full, clear, and exact description 10 of the invention, such as will enable others skilled in the art to which it appertains to make and use the same.

This invention relates generally to games, but more particularly to game boards.

15 The principal object of the invention is to provide a board attachment for pocket billiard tables designed for use in connection with pool or pocket billiard balls numbered from 1 to 15.

20 Another object of the invention is to provide a board attachment of this character having billiard ball receiving openings arranged in a novel and unique manner, and being numbered or colored to correspond 25 with the various numbers and colors of the billiard balls.

A further object is to provide an attachment of this character in which the board is inclined downwardly from the rear to 30 the front thereof to increase the difficulty in lodging the balls in the holes formed in said board.

With these and other objects in view the invention consists of the novel features of 35 construction and the combination and arrangement of parts as will be hereinafter fully described and claimed.

In the accompanying drawing forming a 40 part of this specification in which similar reference characters designate like parts throughout the views,

Figure 1 is a plan view of a board constructed in accordance with this invention.

Fig. 2 is a transverse sectional view of the 45 board taken on the plane indicated by the line 2—2 of Fig. 1.

In the embodiment illustrated the numeral 1 designates a game board composed of a single slab of a length corresponding to the 50 width of a billiard table and of any desired width. The board is designed to be placed across one end of the billiard table with the ends of the board arranged adjacent the side cushions of the table and with its rear edge disposed adjacent one end cushion thereof. 55 The front edge of the board is beveled as at

2 from its upper face and provided with a strip of felt. While the board 1 may be constructed of any suitable material, it is preferably made of five-ply veneer. A strip 2' 60 is secured to the lower face of the board at its rear end to provide for the downward inclination of the board from the rear to the front thereof, said strip being preferably about one-fourth of an inch thick. 65

Painted or otherwise depicted upon the board at approximately the center thereof is a word, preferably "Roulo" the name of the game, and around this is arranged a pair of concentric circles 3 and 4, the outer circle 4 70 being of a diameter slightly less than the width of the board 1 and the inner circle 3 being slightly smaller than the outer circle 4. The numeral 5 designates a number of triangles which are represented on the board 75 with their bases disposed against the inner circle 3 and with their vertices opposite their bases pointing inwardly.

Arranged between the triangles 5 is a plurality of openings 6 of a size capable of receiving billiard balls therein. These openings 6 are disposed in a circle. Arranged in another circle concentric with respect to the circle of openings 6 is a set of openings 7, the latter being disposed between the openings 6 and adjacent the above mentioned vertices of the triangles 5. A central opening 8 is arranged at approximately the center of the board 1 and also centrally of the openings 6 and 7 of the circles 3 and 4. This 90 central opening 8 is also disposed in the letter U of the word Roulo.

The board 1 is also provided with sets of billiard ball receiving openings at its portions between its ends and the circles of 95 openings 6 and 7. These additional openings 9 are arranged in seven rows extending longitudinally of the board. The first and last row of each set contains three openings, the middle row of each set one opening 100 and the remaining rows of each set contain two openings. The openings of the first, last and middle rows of each set are aligned transversely of the board, and the openings of the other row of each set are aligned transversely of the board. 105

There are preferably fifteen of the openings 7 and an equal number of openings in each of the two sets. The openings 7 are numbered in succession from 1 to 15, and 110 the openings 9 of one set are numbered from 1 to 15 starting from one edge of the board

while the openings 9 of the other set are numbered from 1 to 15 starting from the other edge of the board. The triangles 5 and the portions of the board between the 5 circles 3 and 4 adjacent the bases of the triangles are colored to correspond with the colors of the billiard balls designated by the numbers opposite the openings 7. For instance, the triangle opposite the opening 10 numbered 1 is colored yellow, that opposite opening numbered 2 is light blue, that opposite opening numbered 3 is red, that opposite number 4 is purple, that opposite opening numbered 5 is orange, that opposite opening numbered 6 is green, that opposite opening numbered 7 is reddish brown, that opposite opening numbered 8 is black, that opposite opening numbered 9 is yellow, that opposite opening numbered 10 is light blue, 15 that opposite opening numbered 11 is red, that opposite opening numbered 12 is dark blue, that opposite opening numbered 13 is orange, that opposite opening numbered 14 is green, and that opposite opening numbered 15 is reddish brown. The portions of the board between the circles 3 and 4 and between the bases of the triangles 5 are painted any suitable color, preferably dark brown.

30 In using the board it is placed at the head of a pocket billiard table with its ends adjacent the side cushions of the table and with its rear edge, that is, the edge remote from the beveled edge 2, adjacent one of the end 35 sections of the table. At the beginning of the game the set of fifteen billiard balls are racked in the usual manner at the foot of the table. Any suitable set of rules may govern the game, but a few are herein suggested. The cue ball is to be played from the head of the table within about an inch of the inclined or beveled edge 2 of the board 1, and thereafter from the position in which it lies, except in the case of a 40 scratch shot as defined in the game of pool or billiards. If on the break shot the player fails to effect the lodgment of a ball in a hole, he forfeits his chance, but if he succeeds he continues to play until he misses or 45 makes a scratch shot. The numbers adjacent the openings 7 represent the numbers of the ball which they and the triangles represent. Both ball openings on either side at the base of any triangle represent 50 the color. One object of the game is to effect the lodgment of one or more balls into an opening numbered or colored to correspond to the number or color of the ball played, and another object of the game 55 is to effect the lodgment of any ball in the central opening 8. The players score according to their success in shooting the balls 60 in various openings, and the winner may be

one whose score totals a predetermined amount. It is to be understood that the 65 rules of the game may be varied as desired. The above mentioned rules are not necessarily complete or to be followed unless desired, but are merely given by way of example.

70 Various changes in form, proportion and in the minor details of construction may be resorted to without departing from the spirit of the invention as defined in the claims, and the various billiard ball receiving openings may be arranged in different manners, and they may also have different numbering and coloring arrangements.

75 We claim:

1. A game device consisting of a board for arrangement across one end of a billiard table and provided at approximately its center with a billiard ball receiving opening, said board being also provided with concentric circles of billiard ball receiving openings around the center opening and sets of billiard ball receiving openings at both ends on both sides of the circles of openings, triangles depicted upon said board between the openings of the outer circle and with one of their vertices pointing inwardly and adjacent the openings of the inner circle, said triangles being colored to correspond to the various colors 95 of the billiard balls, and numbers depicted on said board adjacent the openings of the inner circle and those of each set to correspond to the numbers of the billiard balls.

2. A game device consisting of a board 100 for arrangement across one end of a billiard table and provided at approximately its center with a billiard ball receiving opening, said board being also provided with concentric circles of billiard ball receiving openings around the center opening and sets of billiard ball receiving openings at both ends on both sides of the circles of openings, triangles depicted upon said board between the openings of the outer 105 circle and with one of their vertices pointing inwardly and adjacent the openings of the inner circle, said triangles being colored to correspond to the various colors of the billiard balls, numbers depicted on said board adjacent the openings of the inner circle and those of each set to correspond to the numbers of the billiard balls, and a word depicted upon said board at the center thereof and adjacent the central opening 110 of the board.

115 In testimony whereof we have hereunto set our hands.

GEORGE DEBELACK.
ALEXANDER DEBELACK.
